UNITED STATES PATENT OFFICE

GEORGE M. McCANN, OF NEW CASTLE, DELAWARE

FIRING MECHANISM

Application filed May 26, 1928. Serial No. 230,855.

(GRANTED UNDER THE ACT OF MARCH 3, 1883, AS AMENDED APRIL 30, 1928; 370 O. G. 757)

The invention described herein, if patented, may be manufactured and used by or for the Government for governmental purposes, without the payment to me of any royalty

5 thereon.

The subject of this invention is a firing mechanism particularly designed as an improvement on the mechanism shown in Patent No. 710,124 of September 30, 1902.

10 In the type of mechanism disclosed in the patent an actuator, a firing pin and a spring are arranged so that the firing movement of the actuator energizes the spring and then releases the firing pin to be driven home by the spring. When the force thus applied to the actuator is removed the rearward action of the spring being directly applied to the actuator through a leverage which is greater than the indirect application thereto through 15 the firing pin of the forward action of the spring produces retraction of the mechanism to the cocked position and retention in this position. The sear which is provided for holding the firing pin during compression of the spring is in the form of a leaf spring and is under a longitudinal strain when struck a transverse blow by the actuator to disengage it from the firing pin. This action has 20 resulted in frequent breaking of the sear. A leaf spring sear of sufficient strength to resist breaking will be deficient in elasticity.

25 In remedying this condition I have formed a sear of a comparatively heavy non-elastic body and have pivoted it on the fulcrum of the actuator so that it becomes a part of the self contained firing mechanism.

With the foregoing and other objects in view, my invention resides in the novel arrangement and combination of parts and in the details of construction hereinafter described and claimed, it being understood that changes in the precise embodiment of the invention herein disclosed may be made within 30 the scope of what is claimed without departing from the spirit of the invention.

A practical embodiment of the invention is illustrated in the accompanying drawings, wherein:

35 Fig. 1 is a longitudinal sectional view

through the firing mechanism showing the parts in the cocked position;

Fig. 2 is a similar view showing the parts in the fired position;

Fig. 3 is a view in rear elevation of a sliding breech block equipped with the firing mechanism;

Fig. 4 is a sectional view substantially on the line 4—4 of Fig. 1;

Fig. 5 is a reduced sectional view on the line 4—4 of Fig. 1 with parts removed;

Figs. 6 and 7 are, respectively, views in plan and side elevation of the sear; and

Fig. 8 is a plan view of the firing pin.

Referring to the drawings by numerals of reference:

In carrying out the invention the breech block 5 is formed with a bore 6 which is closed at the face of the block by a plug 7 having a central aperture 8. A casing 9 containing a firing mechanism is inserted into the bore from the rear of the block and retained by means of a bayonet joint 10.

The firing mechanism which is housed within the casing comprises a firing pin 11, a sleeve 12 slideable on the stem 13 of the pin and a spring 14 confined between a collar 15 on the pin and the base 16 of the sleeve. Extension of the firing pin and sleeve is limited by a lug 17 formed on the upper rear end 75 of the pin and projecting into the path of movement of the sleeve.

Mounted transversely both in the breech block 5 and casing 9 is a shaft 18 to which is fixed an external actuating lever 19 and also an arm 20 placed in line with the firing pin and bifurcated to embrace the stem thereof. The arm is in engagement through the forward face of its extremities 21 with the rear face of the sleeve 12 and it is also in engagement through an intermediate portion 22 whose rear face may bear against lugs 23 on the firing pin with such force. In this manner the rearward and forward actions of the spring are transmitted to the arm 90 with different leverages.

The casing 9 is formed with a longitudinally disposed groove 24 in which is placed a heavy rigid sear 25 formed with spaced bearings 26 embracing the arm 20 and jour-

naled on the shaft 18. The bearing which is on the side from which the shaft 18 is introduced is of a diameter to permit the passage of the squared portion 27 which carries the arm 20. The forward portion of the sear is formed with the usual detent 28 for engaging the collar of the firing pin and with a cam face 29 which is engaged by the sleeve to depress the sear. The intermediate portion of the sear is provided on its outer side with a stud 30 which fits into a helical sear spring 31 set in a recess 32 in the casing.

The operation of the mechanism conforms to that described in the patent previously referred to in which the actuator is considered as the sleeve 12 and the fulcrumed arm 20. The sear 25 which is constructed to withstand the longitudinal and transverse strains to which it is subjected is arranged in a novel manner in the casing containing the firing mechanism.

I claim:

1. A breech block formed with a bore, a casing securable in the bore and having a longitudinally disposed groove, a fulcrumed actuator, a spring confined between the firing pin and actuator, a sear disposed in the casing and having spaced bearings embracing a portion of the actuator and mounted on the fulcrum thereof and a sear spring carried by the casing.

2. A breech block formed with a bore, a casing securable in the bore, a fulcrumed actuator, a spring confined between the firing pin and actuator, a sear disposed in the casing and having spaced bearings embracing a portion of the actuator and mounted on the fulcrum thereof and a sear spring carried by the casing.

3. In a firing mechanism, a casing, a firing pin in the casing, a fulcrumed actuator, a spring confined between the pin and actuator, a sear disposed in the casing and having bearings mounted on the fulcrum of the actuator and a sear spring carried by the casing.

4. A breech block formed with a bore, a casing insertable wholly within the bore and securable therein, a firing pin in the casing, mechanism including an arm fulcrumed in the casing for moving the pin to cocked and fired position, a sear in the casing pivotally mounted on the fulcrum of the arm, and a sear spring.

5. A breech block formed with a bore, a casing insertable wholly within the bore and securable therein, and a firing mechanism including a fulcrumed arm within the casing.

6. In a firing mechanism, a firing pin, mechanism including a fulcrumed arm for moving the firing pin to cocked and fired position, and a sear pivotally mounted on the fulcrum of the arm.

65 GEORGE M. McCANN.
